(57) **CLAIM**

The ornamental design for a robot toy, as shown and described.

DESCRIPTION

FIG. 1 is a front perspective view of a robot toy showing our new design;

FIG. 2 is a rear perspective view thereof;

FIG. 3 is a front elevational view thereof;

FIG. 4 is a rear elevational view thereof;

FIG. 5 is a right side elevational view thereof, a left side elevational view thereof being a mirror image;

FIG. 6 is a top plan view thereof;

FIG. 7 is a bottom plan view thereof;

FIG. 8 is a front view of another embodiment of a robot toy showing our new design; and,

FIG. 9 is a right side elevational view thereof, a left side elevational view thereof being a mirror image.

The portions of the second embodiment that are not disclosed in the drawings are identical to the first embodiment.
